[57] **ABSTRACT**

A silver halide color photographic light-sensitive material comprising a support having thereon a blue-sensitive silver halide emulsion layer, a green-sensitive silver halide emulsion layer and a red-sensitive silver halide emulsion layer, wherein a maximum sensitivity wavelength λ_R of a spectral sensitivity distribution of said red-sensitive silver halide emulsion layer is in a range of $595 \text{ nm} \leq \lambda_R \leq 625 \text{ nm}$; a maximum sensitivity wavelength λ_G of a spectral sensitivity distribution of said green-sensitive silver halide emulsion layer is in a range of $530 \text{ nm} \leq \lambda_G \leq 560 \text{ nm}$; and a sensitivity of said green-sensitive silver halide emulsion layer at 500 nm is not less than one-fourth of the sensitivity at the maximum sensitivity wavelength λ_G .

A statutory invention registration is not a patent. It has the defensive attributes of a patent but does not have the enforceable attributes of a patent. No article or advertisement or the like may use the term patent, or any term suggestive of a patent, when referring to a statutory invention registration. For more specific information on the rights associated with a statutory invention registration see 35 U.S.C. 157.

F I G. I

COLOR PHOTOGRAPHIC LIGHT-SENSITIVE MATERIAL EXCELLENT IN COLOR REPRODUCTION

FIELD OF THE INVENTION

The present invention relates to a color photographic light-sensitive material, particularly to a color photographic light-sensitive material having a high saturation and an excellent hue reproduction.

BACKGROUND OF THE INVENTION

In recent years, a marked improvement has been made in image quality of silver halide multi-layered color photographic light-sensitive materials.

That is, graininess, sharpness and color reproducibility, which are integral parts of the three elements of image quality, are on substantially high levels in recent color photographic light-sensitive materials. In an ordinary color photography, for example, it seems that customers do not complain much of the quality of color prints or slidefilms they obtain.

In the color reproducibility among the three elements, however, color purity has been improved, but colors which are conventionally regarded to be hard to reproduce in photography still remain unimproved; that is, the color reproducibility has problems for solution still now. For example, purple and bluish purple which reflect a ray having a wavelength larger than 600 nm, or green-based colors such as bluish green and yellowish green, are occasionally reproduced in a color quite different from the original, disappointing users of their expectations.

A spectral sensitivity distribution and an interimage effect are decisive factors in the color reproduction.

With respect to the interimage effect, it is known to add a so-called DIR compound which forms a developing inhibitor or a precursor thereof upon reaction with an oxidation product of a color developing agent, to a silver halide multi-layered color photographic light-sensitive material. In this case, a developing inhibitor released from such a DIR compound inhibits developing of other color forming layers and thereby produces an interimage effect to improve the color reproduction.

In a color negative film, the same effect as the interimage effect can be achieved by adding a colored coupler in an amount larger than that necessary to offset useless absorptions.

However, using an excessive amount of a colored coupler causes a minimum optical density of a film to increase; this makes it difficult to form a proper judgement on the correction of color or optical density of print, thereby deterioration in color quality of print is liable to occur.

Meanwhile, these techniques contribute particularly to the enhancement of color purity in the color reproduction. A so-called diffusible DIR compound, which is frequently used in recent years and whose inhibiting group and precursor have large mobilities, contributes greatly to improvement in color purity. But, the interimage effect is difficult to be controlled in a proper direction, thereby it is liable to cause a trouble of changing a color, though it can raise the color purity (directional control of the interimage effect is described in U.S. Pat. No. 4,725,529).

With regard to the spectral sensitivity distribution, U.S. Pat. No. 3,672,898 discloses a spectral sensitivity distribution appropriate to mitigate a fluctuation in

color reproduction caused by a difference in light sources at photographing. But, this is not good enough to improve the foregoing poor-reproducible colors.

As known in the photographic art, color reproductions of bluish purple and purple can be improved by shifting a spectral sensitivity distribution in a red-sensitive layer to a shorter wavelength region. This technique is described in Japanese Patent Publication Open to Public Inspection Nos. 20926/1978 and 131937/1984, but the methods described therein have a couple of shortcomings such as an insufficient color reproduction for purple of the primal object and lowering in color purity of skin color, a fatal drawback for a photographic material.

A combination of a spectral sensitivity distribution and an interimage effect is disclosed in Japanese Patent O.P.I. Publication No. 34541/1986, in which an attempt is made to improve the foregoing poor-reproducible colors and seems to produce an effect to some extent. Its typical embodiment is to exercise an interimage effect not only from a centroidal wavelength of each of blue-sensitive, green-sensitive and red-sensitive layers as performed in conventional methods, but also from wavelengths other than the centroid of each color sensitive layer.

Though this technique seems to be effective in improving reproductions of specific colors to some extent, it costs too much, because of an increased amount of silver consumption owing to necessity for providing an interimage effect producing layer besides primary blue-sensitive, green-sensitive and red-sensitive layers as well as necessity for another type of light-sensitive silver halide, in addition to a high production cost due to increase in the number of processes. Moreover, the effect is not good enough.

SUMMARY OF THE INVENTION

The object of the present invention is to provide a silver halide color photographic light-sensitive material capable of faithfully reproducing bluish purple, bluish green and green without impairing reproduction of skin color.

The present inventors have made an intensive study and found that the object of the invention can be achieved by the following constitution:

A color photographic light-sensitive material having on a support at least one layer each of blue-sensitive silver halide emulsion layer (hereinafter occasionally referred to as a blue-sensitive layer), green-sensitive silver halide emulsion layer (hereinafter occasionally referred to as a green-sensitive layer) and red-sensitive silver halide emulsion layer (hereinafter occasionally referred to as a red-sensitive layer), wherein a maximum sensitivity wavelength λ_R in a spectral sensitivity distribution of said red-sensitive is in a range of

$$595 \text{ nm} \leq \lambda_R \leq 625 \text{ nm}$$

and a maximum sensitivity wavelength λ_G of a spectral sensitivity distribution of said green-sensitive silver halide emulsion layer is in a range of

$$530 \text{ nm} \leq \lambda_G \leq 560 \text{ nm}$$

and a sensitivity of said green-sensitive layer at 500 nm is larger than one-fourth the sensitivity at the maximum sensitivity wavelength λ_G .

BRIEF DESCRIPTION OF DRAWING

FIG. 1 is a chart showing color reproductions of the samples on the (a^*, b^*) plane of the (L^*, a^*, b^*) color system.

DETAILED DESCRIPTION OF THE INVENTION

The present invention will be explained in detail below.

In the spectral sensitivity distribution of the invention, the spectral sensitivity is shown as a function of a wavelength; that is, when a light-sensitive material is exposed to a spectral light from 400 nm to 700 nm at intervals of several nanometers, on the basis of the exposure to give a prescribed density at each wavelength is evaluated a sensitivity of said wavelength.

In the invention, a proper measure can be arbitrarily taken to obtain the foregoing inventive spectral sensitivity distribution in red-sensitive and green-sensitive layers. Use of a spectral sensitizing dye, for example, provides such a spectral sensitivity distribution. Types of spectral sensitizing dyes used in these layers are not limited, but good results can be obtained by using the following spectral sensitizing dyes in combination.

That is, though the spectral sensitivity distribution of a red-sensitive layer can be brought into that specified in the present invention by various means, but such a spectral sensitivity distribution is preferably achieved by a red-sensitive emulsion spectrally sensitized by a combined use of at least one of the sensitizing dyes represented by Formula (I) and at least one of the sensitizing dyes represented by Formula (II) or (III).

wherein R^1 represents a hydrogen atom, an alkyl group or an aryl group; R^2 and R^3 individually represent an alkyl group; Y^1 and Y^2 individually represent a sulfur atom or a selenium atom; Z^1 , Z^2 , Z^3 and Z^4 individually represent a hydrogen atom, a halogen atom, a hydroxyl group, an alkoxy group, an amino group, an acyl group, an acylamino group, an acyloxy group, an alkoxy carbonyl group, an aryl group, an aryloxy group, an aryloxycarbonyl group, a sulfonyl group, a carbamoyl group, an alkyl group or a cyano group, Z^1 and Z^2 and/or Z^3 and Z^4 may bond with each other to form a ring; X_1 represents a cation; and m represents an integer of 1 or 2, or represents 1 provided that the sensitizing dye forms an intramolecular salt.

wherein R^4 represents a hydrogen atom, an alkyl group or an aryl group; R^5 , R^6 , R^7 and R^8 individually represent an alkyl group; Y^3 represents a nitrogen atom, a sulfur atom or a selenium atom, and no R^5 exists when Y^3 is a sulfur or selenium atom; Z^5 , Z^6 , Z^7 and Z^8 individually represent a hydrogen atom, a halogen atom, a hydroxyl group, an alkoxy group, an amino group, an acyl group, an acylamino group, an acyloxy group, an aryloxy group, an alkoxy carbonyl group, an aryloxycarbonyl group, an alkoxy carbonyl amine group, a carbamoyl group, an aryl group, an alkyl group, a cyano group, or a sulfonyl group, Z^5 and Z^6 and/or Z^7 and Z^8 may bond with each other to form a ring; X_2 represents a cation; and n represents an integer of 1 or 2, or represents 1 provided that the sensitizing dye forms an intramolecular salt.

wherein Y^5 represents a sulfur atom or a selenium atom; R^{18} represents a hydrogen atom, a lower alkyl group (e.g., methyl, ethyl and propyl) or an aryl group (e.g., phenyl); R^{19} and R^{20} individually represent a lower alkyl group (e.g., methyl, ethyl, butyl, and an alkyl group having a substituent such as sulfoethyl, carboxypropyl or sulfobutyl); Z^{17} , Z^{18} , Z^{19} and Z^{20} individually represent a hydrogen atom, a halogen atom (e.g., chlorine, bromine, iodine and fluorine), a hydroxyl group, an alkoxy group (e.g., methoxy, ethoxy, propoxy and butoxy), an amino group (e.g., amino, methylamino, dimethylamino and diethylamino), an acylamino group (e.g., acetamide and propiono), an acyloxy group (e.g., ethoxycarbonyl and propoxycarbonyl) an alkoxy carbonyl amine group (e.g., ethoxycarbonyl amine and propoxycarbonyl amine), an aryl group (e.g., phenyl), a lower alkyl group (e.g., methyl, ethyl and propyl), Z^{17} and Z^{18} and/or Z^{19} and Z^{20} may bond with each other to form a ring such as a benzene ring; X^5 represents a cation; and Q represents an integer of 1 or 2, or represents 1 provided that the sensitizing dye forms an intramolecular salt.

Typical sensitizing dyes used in the invention and represented by Formulas (I), (II) and (III) are exemplified below, but the scope of the invention is not limited to them. Among these compounds, (I-1) through (I-46) are those represented by Formula (I), (II-1) through (II-56) are those represented by Formula (II), and (III-1) through (III-12) are those represented by Formula (III).

Besides sensitizing dyes represented by Formulas (I), (II) and (III), supersensitizers such as benzothiazoles and quinolines described in Japanese Patent Examined Publication No. 24533/1982 and quinoline derivatives described in Japanese Patent Examined Publication No. 45 24899/1982 may be used according to a specific requirement.

In combining red-sensitive sensitizing dyes, it is preferred to use at least one sensitizing dye represented by Formula (I) and at least one sensitizing dye represented by Formula (II). Further, it is preferred in this combina-

tion that Y^1 and Y^2 in the sensitizing dye represented by Formula (I) be sulfur atoms and that Y^3 in the sensitizing dye represented by Formula (II) be $N-R^a$, wherein N represents a nitrogen atom and R^a represents an alkyl group.

Further, the green-sensitive layer is brought into the foregoing spectral sensitivity distribution of the invention by adding the following sensitizing dyes singly or in combination. The followings are examples of sensitizing dyes usable in the green-sensitive layer, but useful sensitizing dyes are not limited to them.

A silver halide emulsion used in a color photographic light-sensitive material of the invention can be chemically sensitized by a conventional manner.

An antifogging agent and a stabilizer may be added to the silver halide emulsion. As a binder for said emulsion, gelatin is favorably used (but not limited to gelatin).

Emulsion layers and other hydrophilic layers may be hardened, and may contain a plasticizer and a latex of water-soluble or scarcely soluble synthetic polymer.

The present invention can be preferably applied to color negative films and color reversal films.

In an emulsion layer of a color photographic light-sensitive material of the invention, a color forming coupler is generally used.

Further, there may be arbitrarily used a colored coupler having a correction effect, a competitive coupler and a chemical substance which releases a photographically useful fragment such as a developing accelerator, 35 bleaching accelerator, developer, antifogging agent, chemical sensitizer, spectral sensitizer or desensitizer, upon coupling with an oxidation product of a developing agent.

The light-sensitive material may have auxiliary layers such as a filter layer, anti-halation layer and anti-irradiation layer. There may be contained in these auxiliary layers or emulsion layers a dye which is washed away or bleached out in the developing process.

The light-sensitive material may also contain a formalin scavenger, brightening agent, matting agent, slipping agent, image stabilizer, surfactant, antistain agent, developing accelerator, developing inhibitor and bleaching accelerator.

The support may be any of a paper laminated with 50 polyethylene, polyethylene terephthalate film, baryta paper and triacetylcellulose film.

In forming dye images on a color light-sensitive material of the invention, conventional color-photographic processes can be applied after exposing.

EXAMPLES

The examples of the present invention will be described below, but the embodiments of the invention are not limited to these examples.

In the following examples, addition amounts to the silver halide light-sensitive material is shown by grams per 1 m² unless otherwise specified. Addition amounts of silver halide and colloidal silver are given in terms of silver.

EXAMPLE 1

The layers of the following compositions were formed in sequence on a triacetylcellulose film base to

After photographing a color rendition chart made by 45 Macbeth Co. with each of the samples 101 through 109, the sample was subjected to the following developing process.

Water was added to make 1 l and the pH was adjusted to 10.

Processing (at 38° C.)	50		
Color developing			
Bleaching	3 min 15 sec		
Washing	6 min 30 sec		
Fixing	3 min 15 sec		
Washing	6 min 30 sec		
Stabilizing	3 min 15 sec		
Drying	1 min 30 sec		
	55		
		[Bleacher]	
		Ammonium ferric ethylenediamine tetracetate	100 g
		Diammonium ethylenediamine tetracetate	10.0 g
		Ammonium bromide	150.0 g
		Glacial acetic acid	10 ml

Compositions of processing solutions used in the respective processes are as follows:

60

[Color developer]	
4-amino-3-methyl-N-ethyl-N-(β-hydroxyethyl) aniline sulfate	4.75 g
Anhydrous sodium sulfite	4.25 g
Hydroxyamine ½ sulfate	2.0 g
Anhydrous potassium carbonate	37.5 g
Sodium bromide	1.3 g

65

Water was added to make 1 l, then the pH was adjusted to 6.0 with aqueous ammonia.

[Fixer]	
Ammonium thiosulfate	175.0 g
Anhydrous sodium sulfite	8.5 g
Sodium metasulfite	2.3 g

66

Water was added to make 1 l, then the pH was adjusted to 6.0 with acetic acid.

[Stabilizer]	
Formalin (37% aqueous solution)	1.5 ml
Koniducks (made by Konica Corp.)	7.5 ml
Water was added to make 1 ml.	

From developed films, print was made on color papers (Konica Color PC Paper type SZ) so as to give the same density for the gray color of 0.7 optical density. Then, reproduced colors were subjected to colorimetry with a color analyzer model CMS-1200 made by Murakami Shikisai Co. The results are shown in FIG. 1 by the L* a* b* color system, wherein numbers 1 through 9 correspond to sample Nos. 101 through 109, respectively.

Further, wavelengths which give maximum spectral sensitivities to the green-sensitive and red-sensitive layers of each sample are shown in Table 2.

TABLE 2

Sample No. (invention/ comparison)	Maximum sensitivity wavelength [nm]		Sensitivity ratio of green- sensitive layer (%)*)
	Green-sensitive layer	Red-sensitive layer	
101 (Comparison)	555	635	17
102 (Comparison)	546	635	29
103 (Comparison)	546	645	29
104 (Comparison)	546	580	29
105 (Comparison)	555	615	17
106 (Invention)	546	615	29
107 (Invention)	546	610	29
108 (Invention)	546	615	27
109 (Invention)	546	610	29

*The sensitivity ratio of a sensitivity of the green-sensitive layer at 500 nm to a sensitivity at a wavelength which gives a maximum sensitivity is also shown in Table 2. The term "sensitivity" used here means a sensitivity at a wavelength which gives a maximum sensitivity in a spectral sensitivity distribution at a density of minimum density + 0.7 in the green-sensitive layer, or a sensitivity at 500 nm in the green-sensitive layer.

In FIG. 1, color-reproduced points on a line connecting an original (° mark) and the origin have the same hue as the original.

In the present invention, reproduced points of purple (P), bluish purple (BF), bluish green (BG) and green (G) are near to the original in FIG. 1; that is, they can achieve a hue reproduction faithful to the original.

In FIG. 1, a reproduction point located far from the origin, on a line connecting an original and the origin, means that it has a high color purity (near to the original). It is apparent from FIG. 1 that each of the inventive samples does not cause lowering in purity of skin color.

What is claimed is:

1. A color photographic light-sensitive material comprising a support having thereon a blue-sensitive silver halide emulsion layer, a green-sensitive silver halide emulsion layer and a red-sensitive silver halide emulsion layer, wherein

a maximum sensitivity wavelength λ_R of a spectral sensitivity distribution of said red-sensitive silver halide emulsion layer is in a range of

595 nm $\leq \lambda_R \leq 625$ nm;

a maximum sensitivity wavelength λ_G of a spectral sensitivity distribution of said green-sensitive silver halide emulsion layer is in a range of

530 nm $\leq \lambda_G \leq 560$ nm;

and a sensitivity of said green-sensitive silver halide emulsion layer at 500 nm is not less than one-fourth of the sensitivity at the maximum sensitivity wavelength λ_G .

2. A color photographic material of claim 1, wherein said red-sensitive silver halide emulsion layer contains at least one of the sensitizing dyes represented by Formula (I) and at least one of the sensitizing dyes represented by Formula (II) or (III),

30 wherein R¹ represents a hydrogen atom, an alkyl group, or an aryl group; R² and R³ individually represent an alkyl group; Y¹ and Y² individually represent a sulfur atom or a selenium atom; Z¹, Z², Z³ and Z⁴ individually represent a hydrogen atom, a halogen atom, a hydroxyl group, an alkoxy group, an amino group, an acyl group, an acylamino group, an acyloxy group, an alkoxy carbonyl group, an aryl group, an aryloxy group, an aryloxycarbonyl group, a sulfonyl group, a carbamoyl group, an alkyl group or a cyano group, Z¹ and Z² and/or Z³ and Z⁴ may bond with each other to form a ring; X₁ represents a cation; and m represents an integer of 1 or 2, or represents 1 provided that the sensitizing dye (I) forms an intramolecular salt,

55 wherein R⁴ represents a hydrogen atom, an alkyl group or an aryl group; R⁵, R⁶, R⁷ and R⁸ individually represent an alkyl group; Y³ represents a nitrogen atom, a sulfur atom or a selenium atom, and no R⁵ exist when Y³ is a sulfur atom or a selenium atom; Z⁵, Z⁶, Z⁷ and Z⁸ individually represent a hydrogen atom, a halogen atom, a hydroxyl group, an alkoxy group, an amino group, an acyl group, an acylamino group, an acyloxy group, an aryloxy group, an alkoxy carbonyl group, an aryloxycarbonyl group, a carbamoyl group, an aryl group, an alkyl group, a cyano group, or a sulfonyl group, Z⁵ and Z⁶ and/or Z⁷ and Z⁸ may bond with each other to form a ring; X₂ represents a cation; and n represents an integer

49

of 1 or 2, or represents 1 provided that the sensitizing dye (II) forms an intramolecular salt,

wherein Y^5 represents a sulfur or a selenium atom; R^{18} represents a hydrogen atom, an alkyl group or an aryl group; R^{19} and R^{20} individually represent an alkyl group; Z^{17} , Z^{18} , Z^{19} and Z^{20} individually represent a hydrogen atom, a halogen atom, a hydroxy group, an alkoxy group, an amino or acylamino group, an alkoxy carbonyl or an alkoxy carbonyl amino group, an aryl group, 20

50

an alkyl group, Z^{17} and Z^{18} and/or Z^{19} and Z^{20} may bond with each other to form a ring; X^5 represents a cation; and Q represents an integer of 1 or 2, or represents 1 provided that the sensitizing dye (III) forms an intramolecular salt.

3. A color photographic material of claim 2, wherein said red-sensitive silver halide emulsion layer contains at least one of the sensitizing dyes represented by Formula (I) and at least one of the sensitizing dyes represented by Formula (II).

4. A color photographic material of claim 2, wherein Y^1 and Y^2 in Formula (I) is a sulfur atom and Y^3 in Formula (II) represents $N-R_a$, wherein N represents an nitrogen atom and R_a represents an alkyl group.

5. A color photographic material of claim 3, wherein Y^1 and Y^2 in Formula (I) is a sulfur atom and Y^3 in Formula (II) represents $N-R_a$, wherein N represents an nitrogen atom and R_a represents an alkyl group.
